UNITED STATES PATENT OFFICE.

ELIZABETH S. DUKE, OF CLINTON, MARYLAND.

DESIGN FOR A NURSERY BENCH CHEST.

Application filed March 28, 1929. Serial No. 30,648. Term of patent 3½ years.

To all whom it may concern:

Be it known that I, ELIZABETH S. DUKE, a citizen of the United States, residing at Clinton, in the county of Prince Georges and State of Maryland, have invented a new, original, and ornamental Design for Nursery Bench Chests, of which the following is a specification, reference being had to the accompanying drawing, forming a part thereof.

In the drawing, Fig. 1 is a front elevation of the nursery bench chest, showing my new design.

Fig. 2 is an elevation of one end, and
Fig. 3 is an elevation of the other end.

I claim:

The ornamental design for a nursery bench chest, as shown.

ELIZABETH S. DUKE.
